UNITED STATES PATENT OFFICE

ROBERT H. WHITEHEAD, OF SALT LAKE CITY, UTAH, ASSIGNOR OF ONE-TENTH TO
CHARLES S. MERRILL, OF SALT LAKE CITY, UTAH

NON-LEAKING FOUNTAIN PEN

Application filed December 23, 1929. Serial No. 416,171.

This invention relates to a fountain pen, and more particularly a non-leaking fountain pen. Its principal objects are:

First. To prevent the leaking of the ink into the cap when the pen is not in use, that is to say, when the cap is screwed into place over the point, in what might be called the closed position.

Second. To be simple, efficient and durable. 10 Third. To be susceptible of economical manufacture.

In attaining my objects, I change the general structure of the ordinary fountain pen very little, the principal difference being that 15 in my improved pen, provision is made in the head for a valve seat near the upper extremity thereof. Then, the ink sac is brought down over the head in the usual manner and a valve, preferably spherical, 20 for instance an ordinary steel ball, is positioned in substantial registry with the valve seat, the ball being movably held by the usual barrel.

In the normal position, the ball bears only 25 slightly against the outside of the ink sac, one side of the ball protruding from the barrel to an extent sufficient to allow the ball to be pushed inwardly so as to firmly press 30 against the seat. Thus, when the cap is screwed into its final position on the barrel, the inside surface of the cap contacts the ball and causes the snug seating of the ball, thus preventing the ink in the sac from flowing 35 down into the feed groove of the pen.

The features of this invention for which the protection of Letters Patent of the United States is desired, are collectively 40 grouped in the claims concluding this specification.

In the drawings, which illustrates several specific forms of my invention,

Fig. 1 represents an elevation of an ordinary fountain pen equipped with my im-

provement, the upper portion of the barrel being broken away;

Fig. 2, a vertical center section taken on line 2—2, Fig. 1, the lower part being in elevation;

Fig. 3, a section similar to Fig. 2 but showing the cap screwed clear up into the protective position on the barrel and the ball valve pushed inwardly into an alternate position where it is fully seated;

Fig. 4, a cross-section taken on line 4—4 in Fig. 3;

Fig. 5, a cross-section taken on line 5—5, Fig. 2;

Figs. 6 and 7, vertical center sections illustrating two structural modifications, the upper part of the barrel in each figure being broken away; and

Fig. 8, a vertical center section taken through the ink sac individually.

Referring to the drawings, Figs. 1 to 5 show a fountain pen of one particular type, this being composed of the head 10, having the upper shouldered portion 10—1 around which the ink sac 12 is held frictionally sealed in the usual manner. Around the outside of the ink sac is the barrel 14, the latter being frictionally held at 14—1 on a shouldered portion of head 10. Through the head from top to bottom extends the 70 usual feed passage 15, this passage leading down to the feed member 16 and the pen point 17 in the usual manner.

In equipping this pen with my improvements, the shouldered upper portion 10—1 of the head 10 is made sufficiently long so as to provide room at its upper end for a valve seat 18 and still leave sufficient bearing surface below the valve seat, as at 10—2, for frictionally sealing the ink sac. Just above 80 the feed passage 15 is the space defined between the seat 18 and the inside surface of the ink sac, this space forming a mouth for the feed passage 15.

The valve may consist of a ball 19, which 90

in the normal writing condition of the pen structure is positioned as indicated in Fig. 2, where the resiliency of the soft rubber ink sac 12 tends to push the ball outwardly through a frusto-conical opening 20 formed in the barrel 14. The ball, however, is prevented from passing entirely through this opening, due to the fact that the smaller diameter of the frusto-conical opening is less than the meridian diameter of the ball. Thus, the resiliency of the rubber sac keeps the mouth of the feed passage 15 normally open. When it is desired to put the pen away as for instance into the user's pocket, the cap is applied in the usual way, the mere act of screwing the cap into place gradually pushing the ball 19 inwardly to a position, such as indicated in Fig. 3, where the ball has forced a portion of the soft rubber wall of the sac onto the seat 18, forming a substantially liquid-tight closure between the ink in the sac and the feed passage 15. A clearance space 18-1 may be provided to insure a good bearing on seat 18.

In order to resist the wear and tear upon the sac caused by the frequent in and out movement of the ball 19, it may be desirable to reinforce the circular wall of the sac adjacent its opening, as indicated at 24, Fig. 8, the purpose being to have the ball contact the reinforced portion at a point anywhere along a belt line 24-1, somewhat as indicated by the dotted circle 19-1 in Fig. 8.

In order to facilitate manufacturing operations, it may be desirable to construct the pen as indicated in Fig. 6, where the head 30 has extending through it the cylindrical bore 31, in which is snugly fitted the feed element 32. This feed element may be provided with the enlarged portion 34 which fits snugly into the ink sac. In the enlarged portion is formed the seat 35 to provide the bearing for the ink sac 36 when pushed inwardly by the valve 37. The groove 38 leads from the mouth 33 to the pen-point 39.

In order to readily adapt the pen structure to pen-points of different sizes, it may be further desirable to make the feed member in two parts as indicated in Fig. 7, the lower part 42 being made in various lengths while the upper part 43 may be uniform. The valve seat may be formed at 45 so as to receive the contacting portion of the ink sac when acted upon by the valve 47. The feed mouth, located between the sac and the seat 45 leads into the passage 48, which in turn leads into the feed groove 49 formed in the feed member 42, and so to the pen-point 44.

While specific embodiments of this invention are herein shown and described, it is to be clearly understood that variations within the scope of the accompanying claims, may be resorted to without jeopardizing my patent protection.

Having fully described my invention, what I claim is:

1. A fountain pen, including in combination an ink sac of resilient material, a feed member having a valve seat disposed to contact the inside of said sac, a valve on the outside of said ink sac, said valve being positioned to register with the said valve seat, and a barrel around said ink sac, said barrel having an opening in which said valve is positioned so as to have in and out motion. 75

2. A fountain pen, including in combination, an ink sac, a head extending and having a valve seat within said ink sac; a barrel enclosing said ink sac and having an opening substantially in registry with said valve seat, said head being secured in said barrel; a valve positioned in said opening so as to bear against the outside of said ink sac and protrude outside said barrel, and means for pushing said valve inwardly until a portion of said ink sac bears on said valve seat. 80 85

3. A fountain pen, including in combination, an ink sac, a head extending into said ink sac, means defining a valve seat in said head adjacent a portion of said ink sac, a ball valve on the outside of said ink sac, said ball valve registering with said valve seat, a barrel surrounding said ink sac and connected to said head, means defining an opening in said barrel, said opening located to receive said ball, said ball normally protruding outside said barrel, and a cap for said barrel, said cap being operative to push said ball inwardly, thereby causing a portion of 90 95 said sac to be forced against said valve seat. 100

4. A fountain pen, including in combination, a head, a feed member extending through said head, said feed member having an enlarged portion with a valve formed 105 therein above said head, an ink sac having a portion thereof surrounding said enlarged portion, a valve in registry with said valve seat, a barrel surrounding said ink sac and connected to said head, said barrel having an opening to receive said valve, said valve normally protruding to the outside of said barrel, and means operative to push said valve inwardly and force said sac against 110 115 said seat. 115

5. A fountain pen, including in combination, a head having a bore defined therein, a feed structure consisting of a lower part and an upper part having a valve seat secured in said head, a pen-point adjacent said lower part, an ink sac around said upper part and having a portion adjacent said valve seat, means defining ink passages leading from a point in proximity to said valve seat to said pen-point, a ball in registry with 120 125 said valve seat and bearing on the outside of said ink sac, a barrel having an opening for supporting said valve, said ball protruding outside said barrel and means for forcing said valve inwardly. 130

6. A fountain pen, including in combination, a barrel, an ink sac within said barrel, a member having an ink feed leading from said sac, means defining an ink feed valve seat inside said sac, a ball contacting said sac in registry with said valve seat, a portion of said ball extending beyond the outer surface of said barrel and means for seating said ball.

10 In testimony whereof, I sign my name hereto.

ROBERT H. WHITEHEAD.
